UNITED STATES PATENT OFFICE.

CHARLIE MUSE, OF HARTSHORNE, OKLAHOMA.

SPOKE-TENONING MACHINE.

1,069,568.

Specification of Letters Patent.

Patented Aug. 5, 1913.

Application filed July 1, 1912. Serial No. 707,054.

To all whom it may concern:

Be it known that I, CHARLIE MUSE, a citizen of the United States, residing at Harts-
5 horne, in the county of Pittsburg and State
of Oklahoma, have invented certain new
and useful Improvements in Spoke-Tenon-
ing Machines; and I do declare the follow-
ing to be a full, clear, and exact description
10 of the invention, such as will enable others
skilled in the art to which it appertains to
make and use the same.

This invention relates to wood working,
and more especially to special machines for
cutting the tenons on wheel-spokes; and the
15 object of the same is to produce a portable
and marketable machine for use in the
smaller wagon shops, by means of which the
inner ends of spokes may be cut to a bevel
20 on their sides and with the proper shoulder
on their edges so as to accurately fit the
sockets in the hub. This and other objects
25 are accomplished by constructing the ma-
chine as hereinafter more fully described
and claimed, and as shown in the drawings
wherein—

Figure 1 is a front elevation of this ma-
chine complete, and Fig. 2 is a central verti-
cal section on the line 2—2 of Fig. 1;
30 Figs. 3 and 4 are horizontal sections on the
lines 3—3 and 4—4 of Fig. 1 respectively.

The numeral 1 designates a base having a
hole through it at a proper point, and at op-
posite ends of this hole 2 rise standards 3
35 and 4 having grooves 5 along their inner
edges for guiding a cutter head 6 which by
preference is a plate having a hole 7 through
its body and a yoke 8 connected with its up-
per end. The yoke is centrally pivoted as
40 at 9 to a lever 10 connected by a link 11
with the upper end of the standard 3 and by
a link 12 with a hand lever 13 pivoted in
the other standard 4, and when this lever is
depressed the main lever 10 descends by rea-
45 son of its link connection, and the yoke 8
forces the cutter head 6 downward within
the guides within the standards in a manner
which will be clear.

The numeral 14 designates a table mount-
50 ed upon the standards at some distance
above the base and provided with an open-
ing 15 next the cutter head and with guides
16 between which slides the foot 17 of a
gage 18, said foot having a fork 19 within
55 which is swiveled a head 20 of a screw 21
whose threads engage a nut 22 carried by a
lug 23 on the table, so that when the head

of the screw is turned its swiveled end ad-
justs the gage 18 toward or from the cutter
head 6 and across the table 14. Secured
upon the base 1 beneath the table is an ob-
lique-faced block 25 standing adjacent the
60 hole 2; and against the outer side of the
block rests a gage 26 whose foot 27 has slots
28 engaged by set screws 29 taking into the
base so that the gage may be set toward or
65 from the block 25 as will be clear. One end
of the foot 27 is continued into an arm 30
upturned as shown and forked as at 31—
the obvious purpose of this arm being to
support the spokes when the inner end of
70 the latter rests on the face of the block 25
preparatory to being cut to the proper bevel
to fit the hole in the hub. It will be ob-
vious that the spoke is beveled while it lies
upon the block 25 at the lower portion of the
75 machine, and, conversely, the spoke is
tenoned while it lies upon the table 14 in a
manner which will be made clear below.

The knife for beveling the end of the
spoke is designated by the numeral 35, and 80
by preference its cutting edge 36 stands ob-
lique to a horizontal and is disposed over
the hole 2 as shown, the body of the knife
being adjustably bolted as at 37 to the lower
edge of the cutter head 6 as indicated. The 85
other knife 38 has one end or heel 39 turned
at an angle to its body to form the shoulder
when the edge 40 of this knife forms the
tenon on the spoke; and the body of this
knife is adjustably bolted as at 41 to the cut-
90 ter head 6 at a point above the hole through
said cutter head and on a line about even
with the top of the table 14. Beneath said
hole a chip-gage 45 is loosely attached at
95 its center as at 46 to the cutter head 6, and
is connected by four set screws 48 at its four
corners therewith, so that when these set
screws are adjusted the distance of the ac-
tive edge of this gage from the face of the
100 cutter head may be regulated at will. The
function of this gage is to determine the
thickness of the chips which will be cut out
of the spoke by the edge of the knife 38, the
chip of course falling through the hole in
105 the cutter head and possibly through the
other hole in the base and into a suitable re-
ceptacle or into the waste.

In use the machine is set up as shown in
the drawings, and the inner end of the spoke
is laid upon the face of the block 25 with its
110 body resting in the fork 31 of the arm 30 at
an oblique angle to the face of the gage,

and when the foot 27 of the gage 26 is adjusted properly by means of its set screws, the inner corner of the inner end of the spoke will lie between the two standards 3 5 and 4. The hand lever is then manipulated to cause the main lever to descend, and the cutter head moves downward so that its blade 36 imparts the proper bevel to the edge of the spoke; after which the latter is 10 reversed and the operation repeated. To adjust the angle or the thickness of the spoke at this point, the set screws through the foot 27 of the gage 28 can be set in a manner which will be clear, but the wedge-shaped block 25 and the position of the fork 15 on the outer end of the arm 30 will doubtless remain the same, as they are merely for supporting the spoke while it is being cut.

To shape the opposite side faces of the 20 inner end of the spoke it is moved up onto the table 14. Here the gage 18 is set by turning the thumb screw so that the end of the spoke is fed as far toward the cutter head as necessary, and the gage 45 is adjusted by 25 setting its various set screws so that the proper depth of cut or notch will be made. The hand lever is then manipulated, the main lever 10 moved downward, and the cutter head descends to cause the knife 38 30 with its heel or angular end 39 to pass across the spoke, so that a chip of the proper size is cut therefrom and falls through the hole in the cutter head and into the waste; after 35 which the knife is raised, the spoke inverted, and the operation repeated on the other edge. From time to time the knife blades will be removed and their edges sharpened as will be obvious.

All parts of this machine are simple in

construction and accessible as for cleansing 40 or repairs.

I do not limit myself to the sizes, shapes, proportions or materials, but would probably make most of the parts of metal for the sake of convenience and strength. 45

What is claimed as new is:—

1. In a machine for tenoning spokes, the combination with a base having an opening through it, a pair of guides rising from said base, a table carried by said guides and notched out between them, an oblique-faced block resting on the base, and adjustable gages on said base and table; of a cutter head movable vertically in said guides and having a hole through its body, a blade carried by the lower edge of said head and adapted to taper one side of a spoke when lying on said block, and a second blade carried by said head above the hole therein and comprising a knife with an angular heel 55 adapted to cut a tenon on a spoke when resting on said table.

2. In a machine for beveling the inner ends of spokes, the combination with a base, a gage whose foot is adjustably mounted on 65 the base, and an arm projecting from the foot and forked; of uprights rising from the base, a cutter head vertically movable between them, and a knife blade secured to the cutter head and moving past said gage, 70 for the purpose set forth.

In testimony whereof I have hereunto set my hand in presence of two subscribing witnesses.

CHARLIE MUSE.
